UNITED STATES PATENT OFFICE.

GOTTLLOB BINDER AND FORREST J. COUCH, OF ROCHESTER, NEW YORK, ASSIGNEES TO
AMERICAN LAUNDRY MACHINERY COMPANY, OF CINCINNATI, OHIO, A CORPORATION OF OHIO.

MANGLE.

1,175,636.

Specification of Letters Patent. Patented Mar. 11,

Application filed April 6, 1914. Serial No. 829,786.

To all whom it may concern:

Be it known that we, GOTTLLOB BINDER and FORREST J. COUCH, both residing at Rochester, in the county of Monroe and State of New York, have invented certain new and useful Improvements in Mangles; and we do hereby declare the following to be a full, clear, and exact description of the same, reference being had to the accompanying drawings, forming a part of this specification, and to the reference-numerals marked thereon.

Our invention relates to mangles, and more particularly to the type of machine embodying a steam chest, together with a plurality of ironing rolls coöperating with one surface of the chest, and an apron or belt co-operating with another surface of the chest, and it has for its purpose to provide an improved means for controlling the apron or belt, whereby it is automatically slackened or loosened to relieve it from pressure against the steam chest whenever the rolls are elevated away from the chest.

A further purpose of the invention is to afford means that will effect slackening of the apron only during a portion of the elevating movement of the rolls, without causing any decrease in the tension of the apron during the initial elevating movement of the ironing rolls away from the chest, and in this way allowing more or less play of the ironing rolls relatively to the steam chest while maintaining the apron at a constant pressure, and relieving it only when the rolls are moved a considerable distance away from the chest.

To these and other ends the invention consists in certain improvements and combinations of parts all as will be hereinafter more fully described, the novel features being pointed out in the claims at the end of the specification.

In the drawings: Figure 1 is a view in side elevation, with parts broken away, showing the application of our invention to a usual type of mangle; Fig. 2 is a view in end elevation, and Fig. 3 is an elevation of the opposite end of the machine, with parts broken away.

Similar reference characters in the several figures indicate the same parts.

In the construction shown in the present embodiment, which is illustrated in connection with a known type of flatwork ironing

machine, A designates a frame upon which is mounted the steam chest B, provided upon its upper surface with a series of depressions, in which engage ironing rolls C. The rolls C are mounted upon a holder D, being journaled in boxes E which are arranged on the holder, and the latter is movable vertically with relation to the frame A in order to carry the rolls C toward and away from the steam chest. Each of the rolls C is mounted in boxes E, which are held in place on the holder by means of rods G, these being somewhat smaller than the openings in the boxes through which they pass in order to permit a slight lost motion or vertical play between the holder and the ironing rolls. This enables the rolls to engage the steam chest with a slightly yielding pressure, the pressure being exerted by means of springs H which engage the boxes G and may be adjusted as to tension by the followers I.

In order to actuate the holder D, so as to effect movement of the ironing rolls away from the steam chest when this is necessary for any purpose, we employ roll elevating means, which may be of any suitable character, and preferably comprises one or more shafts J, J¹ upon which are mounted eccentrics that operate, when the shafts are rotated, to effect vertical movement of the connecting rods L, the latter being suitably connected at their upper ends to the holder D. The shafts J, J¹ may be operated in any desirable manner, and to this end are provided with worm gears M, engaged by worms N mounted upon a drive shaft O, which is adapted to be driven by any convenient form of gearing.

Operating beneath the steam chest is a pair of aprons or belts designated generally at P and Q. The upper apron P engages the lower surface of the steam chest in the manner shown, while the lower apron Q is arranged so that its upper portion engages the lower lap of the apron P, guiding rolls being provided to control the path of travel of the aprons as usual in this type of machine. When the ironing rolls are elevating away from the steam chest, or it becomes necessary to stop the operation of the machine for any length of time, it is desirable that the aprons be instantly slackened, so that the upper apron will not be held against the steam chest with sufficient pressure

cause scorching or burning either of the apron or of any articles that may be in the machine. To this end we provide guiding rolls for the aprons, that are mounted upon a movable support, which is actuated from the roll elevating means, by devices that permit the said support to remain stationary during the preliminary or initial vertical movement of the ironing rolls, and effect sufficient movement of the support during the latter part of the upward movement of the ironing rolls to relieve the aprons sufficiently. To this end, we may employ a support consisting of brackets *R* which are pivotally mounted at *a* and are provided with slots or cutaway portions *b* to receive the adjustable boxes *c* in which the guiding rolls *d* and *e* are mounted. The brackets *R* are preferably provided with projections, or anti-friction rollers *f*, which are arranged to engage the edges of cams *g*, upon the shaft *J*¹, the parts being normally in the position shown in Fig. 1, in which the apron guiding roll support is in a nearly vertical position, the aprons being stretched taut. Cams *g* are of such a shape that during a partial rotation of the shaft *J*¹, no movement of the apron guiding roll support takes place, and the pressure of the apron is not changed until the shaft *J*¹ is rotated far enough to bring the narrower portion of the cam into engagement with the support, whereupon the latter is permitted to be lowered to a nearly horizontal position, and the aprons are correspondingly slackened. This allows the ironing rolls to be elevated and lowered slightly, with respect to the steam chest, for varying thicknesses of articles, without affecting the pressure of the aprons and this enables us to obtain the same ironing effect for articles of any thickness that may pass through the machine, the pressure of the aprons not being changed until the ironing rolls have been elevated a considerable distance away from the chest when the ironing rolls are lowered, the reverse operation from what has been described takes place.

It is to be understood that the invention is not limited, in its broadest aspect, to the

particular embodiment disclosed or to any particular form of connection between the roll elevating means and the apron guiding rolls, as we intend to cover by this application any structure which is the equivalent of what we have shown in so far as it may include a means for decreasing the pressure or tension of an apron during the latter part of the upward movement of the ironing rolls, and permitting a certain amount of relative movement between the ironing rolls and chest without affecting the tension of the apron.

We claim as our invention:

1. In an ironing machine, the combination with a steam chest and ironing rolls coöperating therewith, of roll elevating means, apron guiding rolls, a movable support on which the apron guiding rolls are mounted, and a variable connection between said support and the roll elevating means acting to permit the support to remain stationary during the initial part of the elevating movement of the rolls and to move it during the remaining part of such movement.

2. In an ironing machine, the combination with a steam chest and ironing rolls coöperating therewith, of roll elevating means, apron guiding rolls, a movable support on which the apron guiding rolls are mounted, and a variable connection between said support and the roll elevating means acting to move the support at an increasing rate as the rolls are elevated.

3. In an ironing machine, the combination with a steam chest and ironing rolls coöperating therewith, of roll elevating means, apron guiding rolls, a movable support on which the apron guiding rolls are mounted, and a cam driven by the roll elevating means and operating on the support to move it during a portion only of the elevating movement of the rolls.

GOTTLÖB BINDER.
FORREST J. COUCH.
